GLUER

Harold J. Goss, Nashua, N. H., assignor to The International Paper Box Machine Company, Nashua, N. H., a corporation of Maine

Application October 21, 1931, Serial No. 570,116

9 Claims. (Cl. 91—51)

The principal object of my invention is to provide an improved mechanism for applying adhesive to selected portions of blanks or other material.

5 A feature of my invention is a wheel to convey glue, said wheel having pockets of peculiar construction, especially for the purpose of maintaining a uniform quantity of glue and also to prevent throwing off the adhesive at high speeds and 10 also to prevent stringing of the adhesive.

Another feature is scraping means of a certain peripheral dimension with relation to the openings of said pockets.

Another feature is a spiral groove provided on 15 the end of the glue wheel to provide lubrication and to prevent wear between the wheel and the side scrapers.

Other features will be pointed out below.

My gluier represents an advance in the art of 20 spot gluing and especially in the use of spot top gluing which has always presented difficulties. Spot gluing of restricted areas of individual blanks has always formerly been done by transfer segments. The glue builds up on the edges 25 of these segments and consequently it is impossible to accurately determine the quantity of glue that is going to be applied by the segment, this being especially true if there is a skip in the feed of the blanks or a change in speed. Further, as 30 the segment breaks away from the glue supply wheel there is objectionable stringing of the glue. At high speeds the glue actually throws away and gathers onto the machine parts where it can drip down and seriously gum up the mechanism. The transfer type of glue pot is especially 35 objectionable on cellophane applying machines because on these machines the glue control governs the production. In other words a very little glue wrongly placed will cause the cellophane to 40 transfer from the blank to the applying mechanism.

Glue pots have been made using wheels with recesses in them such as that disclosed in U. S. Letters Patent No. 1,793,082 dated February 17, 45 1931. However this type of pot is a bottom glue pot and consequently the pockets are drilled large and shallow as they simply carry around a supply of glue. Neither was it necessary to 50 scrape the remainder of the wheel dry for the purposes to which this pot was put was simply to make the supply of glue in some sections much heavier than the remainder.

With a top glue pot, that is, one in which the 55 glue is applied on top of a blank I have discovered that the holes or pockets should be very

small and very deep compared to their diameter. This type of hole brought astonishing results. The glue was forced up into the holes but never forced the air out of the pockets completely. Thus by using a scraper peripherally longer than 60 the open end of the hole the glue could be compressed into the hole and immediately after passing the scraper it was forced to protrude again by the compressed air in the shape of a pimple or button. The compression being constant the 65 protrusion is constant and gravity or centrifugal force cannot cause the glue to throw off because of the greater pull of vacuum after the pimple or button is formed.

Thus speed has no effect on this glue pot and 70 neither is there any opportunity for the glue to build up to any surplus whether the glue is being used up by blanks or not. A scraper whose active edge is peripherally larger than said open end is essential as otherwise the air pressure built 75 up as the glue is compressed into the holes causes the glue to shoot around or by-pass the scraper and build up onto the under side of the scraper. My single wheel top glue pot permits the glue pot to be completely covered to prevent the evaporation of solvent which is used in some glue and especially the moisture proof cellophane glues.

In the drawings

Figure 1 is a plan of a gluier embodying my invention;

Figure 2 is an elevation thereof;

Figure 3 is an elevation in perspective of a portion of the mechanism;

Figure 4 is an elevation of the scraper and a partial elevation of the glue wheel, on a larger 90 scale; and

Figure 5 is a plan of a blank that has been operated on by the wheel shown in Figures 1 to 4.

Glue wheel or roll 1 is provided at its periphery with pockets or holes 2, these being located to 95 apply glue at the spots or portions of the blank as desired as, for example, at the spots 3 of blank 4 in Figure 5.

Each hole or pocket is preferably substantially cylindrical and extends inwardly from the 100 periphery of wheel 1. The depth of each pocket is very substantially greater than the diameter, or other dimension, of the pocket at the periphery of the wheel for the purposes described above and preferably such depth is more than twice as 105 great as such diameter or other dimension.

Each end face of wheel 1 is provided with a spiral groove 5, (only one being shown) this groove carrying glue to provide lubrication between the side scrapers 6 (to be later described) 110

and the end faces of the wheel and also serving to prevent leakage by preventing wear of the parts, said groove working the glue or other adhesive back into the pot.

- 5 The scraper 7 has an edge 8 tangential to, and preferably contacting with, the wheel and of arcuate form, the dimension of this edge along the periphery of the wheel being at least as great as the opening of the pocket at said periphery, 80
10 the scraper, in the form shown, extending transversely of the machine along the entire length of the wheel and slightly beyond the end faces thereof.

The blank is suitably fed along the path indicated by the line 9 and between the wheel 1 and the corrugated roller 10 which may be operated in any suitable way and preferably at the same surface speed as that of the wheel 1, the glue being deposited on top of the blank.

- 20 The side scrapers 6 rest on the scraper 7 and prevent leakage between the scrapers 6 and scraper 7. Said scrapers 6 may be held in position by screws 11 on the frame engaging recesses 12 in the side scrapers. Shoulders 13 prevent leakage around the side scrapers. Said scrapers 25 are a close fit to the ends of the wheels.

The scraper 7 is attached to the frame by screws 14 and is slotted for adjustability and screw 15 is provided for such adjustment and 30 to give positive pressure against the outer end of the scraper to press the edge 8 against the wheel 1.

Wheel 1 has hub 16 and is keyed to shaft 17 which may be operated in any suitable way. The 35 hubs 16 turn in the bearings of the glue pot which is supported on shafts 17 and 18, the latter being fixed and preventing rotation of the glue pot.

The outer wall of the glue pot is indicated at 40 19, the glue wheel itself forming a wall.

My wheel has pockets of such depth that alternate pressure and vacuum effects are created in the pockets, the depth being such that all the air can not escape. Moreover the pockets are 45 of such capacity compared to the peripheral exposure of the pockets that the adhesive cannot harden in the pockets by oxidation.

It will be clear that the pockets in my wheel are grouped to correspond with certain predetermined areas of the blank to which adhesive is 50 to be applied and that I provide means for removing adhesive from the surface of the wheel adjacent to the pockets and that I provide means to momentarily compress adhesive into said 55 pockets to cause the adhesive to project from the pockets when the compression is over.

What I claim is:

1. A device of the character described comprising a rotary member having pockets which are 60 open at the periphery of said member, the depth of a pocket being greater than twice the distance across its opening; and means to force adhesive into said pockets; and means extending peripherally completely across each pocket to prevent the adhesive from by-passing.

2. The combination of a wheel provided with pockets to receive adhesive, the depth of each pocket being at least twice the distance across its opening to confine air at all times at the base 70 of the pocket to create alternate pressure and

vacuum effects in the pocket; and a member co-operating with said pockets to accomplish said effects.

3. A device of the character described comprising a rotary member having pockets which are open at the periphery of said member, the depth of a pocket being at least twice the distance across its opening to confine air at all times at the bases of the pockets; means to force adhesive into said pockets; and means extending peripherally completely across each pocket to prevent the adhesive from by-passing, the axis of said rotary member and said extending means having a fixed relation when operating.

4. A device of the character described comprising a rotary member having cylindrical pockets which are open at the periphery of said member, the depth of a pocket being at least twice the distance across its opening to confine air at all times at the bases of the pockets; means to force adhesive into said pockets; and means extending peripherally completely across each pocket to prevent the adhesive from by-passing.

5. A device of the character described comprising a rotary member having pockets which are open at the periphery of said member, the depth of each pocket being at least twice the distance across its opening to confine air at all times at the bases of the pockets; means to force adhesive into said pockets; and means extending peripherally completely across each pocket to prevent the adhesive from by-passing.

6. The combination of a wheel provided with pockets to receive adhesive, the depth of each pocket being at least twice the distance across its opening so that all the air in said pockets can not escape; and a member cooperating with said pockets to prevent the escape of all of said air.

7. In a mechanism of the character described 115 a rotary member having a plurality of pockets in its periphery, said pockets grouped to correspond with certain predetermined areas of a blank to which glue is to be applied, the depth of each pocket being at least twice the distance across its opening to confine air at all times at the bases 120 of the pockets; and means to momentarily compress glue into said pockets to cause the air to force the glue from said pockets when the compressing action is over.

8. In a mechanism of the character described 125 a rotary member comprising pockets in its periphery, the depth of each pocket being at least twice the distance across its opening to confine air at all times at the bases of the pockets; and means for removing glue from the surface of said member adjacent to said pockets and to momentarily compress glue into said pockets to cause said air to effect a projection of the glue from the pockets when the compressing action is over.

9. A device of the character described comprising 135 a rotary member having pockets which are open at the periphery of said member, the depth of a pocket being at least twice the distance across its opening to confine air at all times at the bases of the pockets; and a member having one face to force adhesive into said pockets and having another face extending peripherally completely across each pocket to prevent the adhesive from by-passing.

HAROLD J. GOSS. 145
